 land

Application February 1, 1933, Serial No. 654,742
 In Great Britain February 2, 1932

13 Claims. (Cl. 194—10)

This invention is for a coin-freed delivery or vending machine and is concerned with a machine having a number of positions at which coins may be inserted and a corresponding number of positions at which goods are delivered.

An important object of the invention is to ensure that upon the insertion of a coin the goods are delivered only to the correct position. Another object of the invention is to render the machine unresponsive to the insertion of a further coin at some other position until delivery has been effected in response to the first inserted coin.

A preferred construction of machine in which these objects are attained will now be described in detail by way of example with reference to the accompanying drawings, in which

Figure 1 is a general arrangement of the machine, and

Figures 2 and 3 are details of an enlarged scale of alternative mechanism at the coin-insertion positions.

Throughout this description like reference numerals indicate like parts.

The machine shown in the drawings has a plurality of vending positions at each of which there is a coin-insertion slot, which slots are numbered 19a, 19b, etc., and an equal number of goods-delivery positions corresponding thereto, there being a number of subsidiary delivery chutes numbered 11a, 11b, etc., which lead off from the main chute 11, one to each vending or delivery position, and the arrangement is such that following the insertion of a coin into the coin slot at any selected vending position only the subsidiary track which leads to that position is prepared to deliver goods. The machine may be said to incorporate devices responsive to the insertion of a coin at any selected insertion position for ensuring the delivery of goods only to the associated delivery position, and for rendering the machine unresponsive to a further selection until after delivery, and delivery-operated means for then rendering the machine again responsive to selection.

It will be observed that at the mouth of each subsidiary chute there is a hinged trap-door 12 which is arranged to cover the mouth of that chute, and the arrangement of the machine is such that when a coin is inserted at any position the appropriate trap-door is opened so that it is inclined across the main chute 11, and a package of goods delivered down the said main chute is deflected by the trap door into the appropriate delivery chute and is carried by the latter to the position at which the coin was inserted. These trap-doors are worked by electro-magnetic mech-

anism. For each vending or delivery position there is a control solenoid, which solenoids are numbered 13a, 13b, etc., and alongside each solenoid there is a vertical rod 14, the lower end of which is coupled by a link 15 to a lever 16 attached to the trap-door 12 of the appropriate subsidiary chute. The rod 14 is provided with a collar 17 and is normally held in a raised position in which the trap-door is closed by means of a pivoted catch 18, which catch is biassed by a spring 19 to an engaging position and is attached by a rod 20 to the base of the plunger 21 of the associated control solenoid. When a coin is inserted in any selected coin slot 10, the associated solenoid 13 is energized, through contacts 15 and a circuit hereinafter described, and the catch 18 is rocked so that the rod 14 drops and opens the appropriate trap-door 12. Thus goods are delivered down the main chute, passing of necessity to the position at which the coin has been inserted. It is desirable, however, that immediately a coin has been inserted at any selected position and the track leading to that position has been prepared for delivery, the machine shall be rendered unresponsive to any further selection 25 until delivery has actually been effected, otherwise it might be possible by inserting a coin at a second slot either to cause a jam in the machine or to cause the goods really purchased by the first coin to be delivered to the position at which 30 the second coin is inserted. To this end the descent of any rod 14 serves to close a circuit through a common solenoid 22 which operates 35 mechanical catches to lock all the other rods 14 against movement, even if the solenoids 13a, 13b, etc., associated therewith are energized. To this end each rod 14 carries a contact pin 23 so placed that when the rod drops said pin makes contact with a spring contact 24 and hence closes the 40 circuit through the common solenoid 22. The armature 25 of the latter is therefore moved to the left and carries with it a horizontally extending rod 26. On this rod there are a number of pins 27, each of which bears against the free end 45 of a leaf-spring 28 attached to a pivoted catch 29, these catches being so arranged that when the solenoid 22 is energized they are biassed by their springs into positions in which they lie beneath the collars 17 on the associated rods 14 and prevent the descent of said rods sufficiently to 50 open their associated trap-doors. It may be pointed out that this locking apparatus does not operate until after the trap-door at the mouth of the selected chute has been opened.

The machine is thus rendered unresponsive to 55

- any further selection but it is, of course, necessary to render it responsive to a fresh selection immediately a delivery has been effected. Therefore, means are provided in each track, actuated by the passage of goods along said track, to break the circuit through the common solenoid 22 so that the armature or plunger 25 thereof moves to the right and the spring pressure on the catches 29 is released, with the result that these catches, 5 by reason of the balance weights 30 with which they are provided, move to inoperative positions. To this end inside each subsidiary chute there is a flap 31 which is connected to the trap door 12 of that chute, the angle between the trap-door 12 and flap being approximately equal to the obtuse angle included between the main chute and each subsidiary chute, so that when the trap-door is opened the flap 31 projects upwards as is shown in Figure 1. Hence, when goods are delivered 10 down the selected subsidiary chute this flap 31 is depressed by the passage of the goods over it and hence serves to close the trap door 12 and to raise the associated rod 14, thus breaking the contacts 23, 24 and breaking the circuit through the common solenoid 22, so that the machine is again rendered responsive to a fresh selection.
- It will be noticed that the catches 29 are placed somewhat lower than the catches 18, so that if, before delivery is completed in response to one 15 coin-insertion or selection, a coin is inserted at another position the rod 14 appropriate to that position is released by its catch 18 and falls a short distance until the collar 17 on it is held by the adjacent catch 29. From this position the 20 rod may complete its downward movement, so that the machine responds to the fresh selection, immediately delivery has been effected in response to the first selection and the common solenoid 22 de-energized by such delivery.
- 40 The coin-receiving mechanism at each vending position and the contacts whereby the circuit is established through the appropriate solenoid 13 is shown somewhat diagrammatically in Figure 1, but Figures 2 and 3 show alternative arrangements on a larger scale. The machine is arranged to deliver goods upon the receipt of two coins at any selected vending position, and referring now to the construction shown in Figure 2 the coin insertion slot 10a leads to a main vertical coin chute 32 from which a subsidiary coin chute 33 leads off at an angle, both of said chutes terminating in a coin receptacle 34. Just below the branch of the two chutes there is a pivoted lever 35 having at its lower end a hook 36 that projects across the main chute 32, so that the first coin inserted into the slot 10a falls down and rests upon this hooked end 36. The second inserted coin strikes the top of the first coin and is deflected thereby down the branch chute 33, 45 where it makes contact with an arm 37 and in so doing establishes an electrical connection between this arm and the chute 33 to complete a circuit through a solenoid 38a. This solenoid is thereby energized and its core 39 is sucked down, 50 movement of said core serving to release the said coins so that they fall to the receptacle 34 and also to complete the circuit through the associated solenoid 13a, whereby the appropriate delivery chute 11a is prepared for delivery.
- 70 It will be seen that the core 39 is connected by a vertical rod 40 to one end of a lever 41, the other end of which is connected by a vertical link 42 to the rocking lever 35. Therefore when the core is sucked down the lever 41 is rocked 75 against its balance weight 43 and the hooked end

36 of the lever 35 is removed from its obstructive position in the main chute 32 so that the first coin falls down into the receptacle 34. It will also be seen that the contact arm 37, against which the second coin rests, is pivoted about a pivot 44 and has attached to it an arm 45 which is connected by a depending hook 46 to the lever 41, and hence as the latter is rocked this contact arm 37 is moved out of its obstructive position in the subsidiary coin chute 33 and the second coin is permitted to fall down to the receptacle 34, so that the circuit is broken through the solenoid 38a. That movement which breaks the circuit through the solenoid 38a, also serves to complete the circuit through the solenoid 13a so that the associated delivery chute is prepared for delivery, because attached to the contact arm 37 there is a further contact arm 47 which upon such movement is brought against a stationary contact 48, these two contacts 47, 48 being included in the circuit of the solenoid 13a. Immediately afterwards the solenoid plunger 39 is returned to its upper position by the balance weight 43 so that the lever 35 and the arm 37 are returned to their obstructive positions and the circuit through the solenoid 13a is broken.

In the alternative arrangements shown in Figure 3 and hereinafter described with reference to a second coin-insertion position, the first coin inserted into the slot 10b falls down the vertical coin chute 132 and comes to rest on a pivoted hook 49 and in falling it comes into engagement with the tail portion 50 of a pivoted pawl 51 so as to swing the said pawl on its pivot and to bring an inclined tip 52 thereof into such a position at the junction between the main vertical chute 132 and the branch chute 133, as indicated in dotted lines, that a second coin inserted in the slot 10b is deflected by this tip 52 down the branch chute. In its passage down the branch chute 133 the second coin falls on to the extremity of a comparatively long lever 53 and depresses said lever until the coin falls clear of the bottom of the chute 133. The said lever 53 is pivoted at 54 and attached to its pivot there is an insulated block 55 carrying a spring bridge-contact member 56, which, upon depression of the lever 53 by the coin, makes contact with and bridges a pair of spaced contacts 57 and in so doing completes the circuit of the appropriate solenoid 13b. The pivot 54 also carries a catch 58 which, upon depression of the lever 53, pushes a pivoted pawl 59 to the left and catches under the lip of this pawl and serves to hold the contacts 56, 57 in engagement until the delivery of the goods has been effected, after which, through the medium of a rod 60 (which is suitably coupled to the appropriate one of the rods 14 shown in Figure 1) a pivoted bell-crank-lever 61 and a hook 62 which coacts with a pin 63 on the pawl 59, the said pawl 59 is pulled out of engagement with the catch 58. When the lever 53 has been depressed by the second inserted coin the first inserted coin is released from the hook 49 by means of an arm 64 and a coupling rod 65 which extends between said arm and the hook 49, and when the hook 49 has been swung from its obstructive position in the chute 132 to permit the first coin to fall the pivoted pawl 51 (hitherto maintained in its obstructive position by the first coin) is swung back by gravity to its normal position in which its tail portion 50 projects through the chute 132 and the tip 52 is withdrawn from said chute. After the delivery of the goods and the disengagement of the catch 58 on the pivot 54 from 75

the pawl 59, a counterweight 66 raises the lever 53 to its normal position and disengages the contacts 56, 57.

Whichever of the two constructions illustrated in Figures 2 and 3 is adapted, it may be desirable to provide means whereby the attendant may obstruct the coin slot to prevent the insertion of coins. For example referring now to Figure 2, there may be a pivoted arm 67 which is normally held clear of the slot 10a but which when a chain 68 or the like is pulled by the attendant is moved across the slot to obstruct it.

We claim:—

1. In a coin-free or operated vending or delivery machine having a plurality of coin-insertion positions and a plurality of goods-delivery positions corresponding thereto the combination of delivery tracks leading one to each delivery position, and electromagnetic devices for preparing, upon the insertion of a coin at a selected position, the corresponding track for delivery and for locking all other tracks against delivery until such delivery has been effected, which devices are in circuit with and include contacts at each insertion position for actuating said devices upon the insertion of a coin.
2. In a coin-free or operated vending or delivery machine having a plurality of coin-insertion positions and a plurality of goods-delivery positions corresponding thereto the combination of delivery tracks leading one to each delivery position, coin-operated contacts at each coin-insertion position, electro-magnetic devices one for each position, actuatable upon such insertion to prepare the associated track for delivery, a further electromagnetic device common to all tracks for locking all other tracks against delivery following the preparation of the selected track and until delivery along said track, means actuated from the selected device for rendering said common device operable, and means for rendering said common device again inoperative subsequent to delivery along the selected track.
3. In a coin-free or operated vending or delivery machine having a plurality of coin-insertion positions and a plurality of goods-delivery positions corresponding thereto the combination of delivery tracks leading one to each delivery position, coin-operated contacts at each coin-insertion position, electro-magnetic devices one for each position, actuatable upon such insertion to prepare the associated track for delivery, a further electromagnetic device common to all tracks for locking all other tracks against delivery following the preparation of the selected track and until delivery along said track, means actuated from the selected device for rendering said common device operable, and means for rendering said common device again inoperative subsequent to delivery along the selected track, said means comprising a member on each track displaceable by the passage of goods over it to break a circuit through said common device.
4. In a coin-free or actuated delivery or vending machine having a plurality of coin-insertion positions and a plurality of goods-delivery positions corresponding thereto the combination of a plurality of delivery tracks leading one to each delivery position, a plurality of electro-magnetic control devices, whereof one is allocated to each track for preparing said track for delivery upon energization of said device, for each control device contacts in circuit therewith at the appropriate coin-insertion position for energizing said device upon the insertion of a coin at said position, a closure for each track, operating connections extending between each closure and the appropriate control device for opening said closure upon energization of said device, electromechanical means for locking, upon the energization of any selected control device, the operating connections of all other devices, and means actuated by delivery of goods down the track the closure whereof is opened as aforesaid for releasing said connections from the lock imposed by said electro-mechanical means.
5. In a coin-free or actuated delivery or vending machine having a plurality of coin-insertion positions and a plurality of goods-delivery positions corresponding thereto the combination of a plurality of delivery tracks leading one to each delivery position, a plurality of electro-magnetic control devices, whereof one is allocated to each track for preparing said track for delivery upon energization of said device, for each control device contacts in circuit therewith at the appropriate coin-insertion position for energizing said device upon the insertion of a coin at said position, a closure for each track, operating connections extending between each closure and the appropriate control device for opening said closure upon energization of said device, electro-mechanical means for locking, upon the energization of any selected control device, the operating connections of all other devices, a flap in each track which flap is movable upon the passage of goods over it, connections between each flap and the closure of that track for closing the latter upon such movement of the flap, and connections between each flap and the said electro-mechanical means for rendering the latter inoperative upon such movement.
6. In a coin-free vending machine having a plurality of coin-insertion positions and a plurality of goods-delivery positions corresponding thereto the combination of a plurality of delivery chutes leading one to each delivery position, a movable trap-door for opening and closing each chute, in each chute a movable flap connected to the trap-door thereof for closing the latter upon delivery of goods down said chute, a plurality of movable trap-opening members connected one to each trap-door and flap, a plurality of electro-magnetic control devices allocated one to each said trap-opening member and each coin-insertion and delivery position and each operable upon energization to permit the associated member to make an opening movement, means for selectively energizing any one of said control devices, said means comprising for each control device contacts at the associated coin-insertion position movable upon the insertion of a coin to complete a circuit through said control device, an electromagnetic locking device, means for energizing said locking device upon opening movement of any selected trap-opening member, a plurality of locking mechanisms movable by said locking device upon energization thereof to lock all other trap-opening members against opening movement, and means operated by the movement of the selected flap consequent upon the delivery of goods over it to de-energize the locking device and thereby to release said locking mechanism.
7. In a coin-free delivery or vending machine having a plurality of coin-insertion or vending positions, a plurality of delivery tracks leading from a common source one to each position, and devices operable upon the insertion of two coins at any selected position for effecting delivery of goods only to the position whereat the coins were

- inserted, the combination, at each coin-insertion position, of a main coin chute, a branch chute diverging therefrom, removable means for temporarily arresting the first inserted coin with-
 5 in the main chute at a position below the fork between the two chutes, means operating by the detention of the first coin in said position to divert a second inserted coin down the branch chute, and means operable by the coin in the branch chute for calling into operation the afore-
 10 said devices and for releasing both coins.
8. In a coin-free delivery or vending machine having a number of coin-insertion positions and delivery positions corresponding thereto and operable upon the insertion of two coins at any selected insertion position the combination with a plurality of delivery tracks leading one to each delivery position, of the following mechanism at each coin-insertion position, a main coin-
 15 chute, a branch chute diverging therefrom, means for temporarily arresting the first inserted coin in the main chute below the fork between the two chutes, said arrested coin serving to deflect the second inserted coin into the branch chute, means
 20 operated by said second coin for preparing for goods-delivery only the track associated with said insertion-position, and means for releasing the first coin.
9. In the combination claimed in claim 8, the provision at each coin-insertion position of a catch interposed in the main chute for arresting the first coin but removable from its obstructive position to release said coin, an electromagnet, coin-operated means for energizing said electromagnet upon the entry of the second coin into the branch chute, means operable by said electromagnet for preparing the corresponding delivery track for delivery, and means operable by said electromagnet for temporarily withdrawing the catch from the main chute.
 30
10. In a vending machine having a plurality of vending and delivery locations at each of which is a token receiving means constructed to receive identical tokens and to be responsive thereto; a plurality of material delivery tracks leading from a common source, one to each such location, and means operable directly by identical means such as tokens by a vendee at any selected delivery location for effecting delivery of goods only at such location.
 40
11. In a vending apparatus having a plurality of vending and delivery stations, the combination of a common track along which the goods to be vended pass from a common store, a plurality of branch tracks leading from the common track individually to the respective vending and delivery stations, means for directing the passage
 45
- 50
- 55

of goods from the main track to an individual track, individual devices arranged in a closely assembled group for controlling the movements of said directing means, token actuated means at each vending and delivery station constructed to be operated by identical tokens, means between the individual token actuated means and the individual control means by which the latter are actuated upon the insertion of a token to cause the control means for the track to the station where the token is inserted to be operated, and a common means for locking all the other control devices whenever one of them is actuated by the token operated means until delivery of the goods to the branch track has been effected.
 5

12. In a coin-operated vending machine having a plurality of coin-insertion positions, a store for vendable goods, and mechanism for withdrawing quantities of goods from said store, the combination of a plurality of delivery tracks leading one to each coin-insertion position and devices operable upon the insertion of a coin at any position to set said mechanism in operation and to deliver the goods only to that position whereat the coin was inserted, including electric contacts at each coin-insertion position arranged to be closed by the insertion of a coin, a plurality of electro-magnets, allocated one to each coin-
 20 insertion position and each controlling the delivery track to the position with which the said electro-magnet is associated, each electro-magnet being operable upon the insertion of a coin at the appropriate position to prepare the delivery track for delivery to such position.
 25

13. In a coin freed or operating vending machine including a store for vendable goods, and mechanism for withdrawing quantities of goods from said store, and having a plurality of coin-
 30 inserting positions at which are located means constructed to receive identical coins and operatively respond thereto, the combination of a plurality of delivery tracks leading one to each coin-
 35 insertion position, closure means for controlling the entrance to the individual tracks, devices operable upon the insertion of a coin at any position to control the closure means for the track individual to that coin-insertion position so as to deliver the goods to that position whereat the coin was inserted, and means operable, upon the preparation of any track for delivery operation, to lock all other tracks against use until delivery to the selected position has been effected.
